OIL DISTILLING APPARATUS

László Hunyadi and Imre Koch, Budapest,
Hungary

Application December 7, 1936, Serial No. 114,700
In Hungary September 19, 1936

4 Claims. (Cl. 196—110)

This invention relates to apparatus for distilling oil and may be used with advantage for the recovery of used oil, although it is not confined to such use.

5 When used oil is heated in a pipe coil for the purposes of distillation the oil easily becomes cracked.

If steam is passed through the oil the partial pressure is reduced and the distillation may be 10 effected at a lower temperature with greater economy, but too much steam is used.

It has been proposed to provide apparatus wherein oil is heated under pressure in a pipe coil and is injected in hot condition into an expansion space, wherein it is converted into vapor form, the vapor being then subjected to fractional condensation in condensing towers. This apparatus has the disadvantage of taking up too 15 much space and of being uneconomical, since all the oil, including the low boiling point parts, has to be heated to the temperature of the parts of the highest boiling point, so that the danger of cracking is again entailed.

In contrast to the two types of apparatus referred to above, the apparatus according to the invention enables the oil to be distilled for recovery, the oil is not subjected to undue pressure, is not heated to undue temperature and there is no danger of cracking, which is of particular importance in the case of lubricants. The low boiling point hydrocarbons are driven out at the early stages of heating at low temperatures, so that the distillation is economical, the quantity to be heated being steadily reduced, while at the 20 same time the oil is more delicately handled. Steam is caused to flow in one and the same pipe coil in counterstream to the oil. The pure steam first meets the oil in which there is least of the fractions to be separated, while the steam laden

25 with the separated fractions, i. e. the impure steam, meets the stream of oil which contains most of the fractions to be separated. Moreover, the fresh steam also penetrates through the oil mists or oil cascades formed in the oil stream 30 containing most of the fractions to be separated. Thus, there are two steam actions at work. One is due to the steam flowing above, i. e. in opposition to, the oil stream, and the other to the fresh steam penetrating through the oil stream, 35 or through the oil mists formed therein.

The upper stream of steam flowing above and in opposition to the oil stream draws along with it by partial pressure effect the fractions floating above the oil stream or liberated therefrom, thereby 40 assisting the evaporation of the oil. The fresh

steam penetrating through the oil stream or the oil mists (oil cascades) makes contact with the elementary particles of the oil and facilitates the liberation of the fractions to be removed.

The apparatus is further distinguished by 45 simple construction, small space requirement, fuel economy, elimination of the danger of cracking, and great output.

Apparatus according to the invention for the distillation of oil is characterized by a partition 10 in the pipe coil for the oil and steam, said partition extending in the direction of the axis of the pipe and dividing it into two chambers, and by apertures in the partition for forming oil mists or oil cascades.

Two embodiments of the invention are illustrated by way of example in the accompanying drawing, wherein:—

Fig. 1 is a part sectional side elevation of one embodiment,

Fig. 2 is a plan view of same partly in section on the line A—B of Fig. 1,

Fig. 3 is a part sectional fragmentary side elevation of another embodiment,

Fig. 4 is a cross sectional view on a larger scale 25 of the oil and steam pipe on the line C—D of Fig. 5 and

Fig. 5 is a fragmentary longitudinal sectional view of same, also on a larger scale.

Referring to Figs. 1 and 2, the annular water tank 1 communicates through a pipe 2 with the lower part of the boiler 4 surrounding the furnace 3. The furnace 3 is associated with a fuel chute 5, grate 6, ash pit 7 and ash pit door 8.

The lower part of the annular oil tank 9 communicates with the oil pipe coil 12 through a pipe 10, which passes through the shell 11 of the oil distilling apparatus and may be wholly or partly closed by a valve 10x.

The steam space of the boiler 4 communicates 40 through a pipe 13 with the superheater pipe coil 15. The pipe 13 is disposed within the shell 11 and in the lower part of the flue 14 joining the truncated cone shaped upper end of the shell.

The lower end of the pipe coil 15 communicates 45 with the common oil and steam pipe coil 16.

The pipe coil 16 is composed of straight sections (Fig. 2) to facilitate cleaning, so that in plan view the pipe coil represents a square figure. The individual straight sections may be easily 50 cleaned after unscrewing their end caps 16x. The lower end of the pipe coil 16 joins the U-shaped 16y discharge tube for the distilled oil, which forms a liquid seal and prevents steam from blowing out.

The pipe coil 16 is divided by the partition 17 in the direction of the pipe axis into an upper larger oil space 18 and a lower smaller steam space 19 (Figs. 4, 5). The partition 17 is trough shaped and the distance apart of its edges equals the inner diameter of the pipe 16.

The spaces 18 and 19 communicate with one another through the transverse slits 17x formed in the partition 17. The lower edge of the slits 17x is dished downwardly towards the steam space 19, so that the layer of oil 20 flowing downwardly on the sloping partition 17 forms, over the slits 17x, oil mists if the layer of oil is shallow and oil cascades if the layer of oil is deep.

Without departing from the spirit of the invention the higher edge of the slits 17x may be dished upwardly towards the space 18, or the higher edge of the slits may be dished upwardly and their lower edge downwardly.

The steam can only pass from the lower space 19 into the upper space 18 through the oil mists or oil cascades, so that the steam passes completely through the oil mists, makes contact with the elementary particles of the oil, thus liberating the particles of lower boiling point and carrying them with it into the space above the oil. The pure steam first meets the oil which contains least of the fractions to be separated, while the steam laden with the separated fractions, i. e. the impure steam, makes contact with the oil stream which contains most of the fractions to be separated. Moreover, the fresh steam also passes through the oil mists or oil cascades formed in the oil stream containing most of the fractions to be separated.

The partition 17 is preferably made of strips of thin sheet steel, which are slightly curved in transverse direction prior to being pushed into the straight tube section 16. No special packing is necessary at the edges of the partition. Where the tube sections 16 join one another the ends of the strips forming the partition overlap flat, thereby ensuring a continuous path for the oil stream.

Connected to one of the upper convolutions of the pipe coil 16, or to the upper space 18 thereof, there is a pipe 21 which leads off the lower boiling point hydrocarbons driven out by the distillation process, together with the steam, to a condenser of any suitable construction.

In the embodiment shown in Fig. 3, pipes 21a, 21b, 21c are connected to the pipe coil 16 at various levels, whereby three different fractions may be separated.

The combustion gases effectively pre-heat the

pipe coil 15, the oil and steam pipe coil 16, pipes 13, 21 (or 21a, 21b, 21c) and the tanks 1 and 9.

The apparatus according to the invention may also be utilized for the distillation of crude oil. In this case the number of pipes 21 will correspond to the number of fractions desired. The pipe 16 may be of polygonal or elliptical section instead of being circular in section.

We claim:—

1. An oil distilling apparatus, including a pipe coil for steam and oil, the coil being divided into two spaces by a trough shaped partition extending in the direction of the axis of the tube forming the coil and the partition having slits for the passage therethrough of steam for forming oil mists or oil cascades in the oil.

2. An oil distilling apparatus, including a pipe coil for steam and oil formed of circular section pipe, the coil being divided into two spaces by a trough shaped partition extending in the direction of the axis of the tube forming the coil, the distance apart of the edges of the partition being equal to the inner diameter of the tube, and the partition having slits for the passage therethrough of steam for forming oil mists or oil cascades in the oil.

3. An oil distilling apparatus, including a steam boiler, a pipe coil for steam and oil divided into two spaces by a partition extending in the direction of the axis of the tube forming the coil, the partition having slits for the passage therethrough of steam for forming oil mists or oil cascades in the oil, and a steam superheating pipe coil disposed within the pipe coil for steam and oil in the path of the combustion gases from the steam boiler, one end of said superheating pipe coil being connected to the steam space of the boiler and the other end of said superheating pipe coil being connected to the lowermost convolution of the pipe coil for steam and oil.

4. An apparatus for distilling oil including a heat flue, a coil disposed in said flue and having a transverse partition provided with openings, means for flowing oil downwardly through said coil over the top of said partition and across the openings, means for supplying steam to the lower end of the coil and to the space below said partition whereby the steam will flow inwardly in said coil and pass through the openings in the partition to bubble through the oil, means at the bottom of the coil for collecting oil, and means at the top of the coil for conducting away the combined steam and fractional oil vapors.
